UNITED STATES PATENT OFFICE.

HARRY W. DENHARD, OF SAN FRANCISCO, CALIFORNIA, ASSIGNOR TO GEORGE B. KATZENSTEIN, JR., OF SAN FRANCISCO, CALIFORNIA.

ATTACHMENT FOR ELECTRIC APPLIANCES.

941,979.

Specification of Letters Patent. Patented Nov. 30, 1909.
Application filed August 7, 1908. Serial No. 447,451.

To all whom it may concern:

Be it known that I, HARRY W. DENHARD, a citizen of the United States, residing at San Francisco, in the county of San Francisco, State of California, have invented new and useful Improvements in Attachments for Electric Appliances, of which the following is a specification.

My invention is designed to take the strain 10 from terminal connections of electrical conductors, and I accomplish this in a very simple and economical manner by the interposition of a ring, or eye located in proximity to the terminals and held in place by 15 the branching or diverging ends of the joined conductors.

In the accompanying drawing, I have shown in Figure 1 a perspective of my invention, and in Fig. 2 an application of the 20 invention.

As is well known electrical conductors are usually arranged in pairs joined together by a suitable covering, the ends diverging, and provided with terminal pieces of various 25 sorts adapted for connection with the device to which the current is to be applied.

In the drawing the joined conductors are shown at 2, and the separate conductors at 3—4. They have attached to them the terminal pieces 5—6, of any suitable construction. At the juncture of the individual conductors with the twin conductor I locate an eyelet or ring 1, the single conductors simply 30 passing around this ring which is made with a concave outer periphery, and the single conductors are knotted as shown in the drawing, which is ordinarily sufficient to hold the 35

ring or eyelet in place. If desired however, and for greater security the metal of the ring may be indented to grip the fabric of 40 the conductors and prevent displacement. In order to prevent separation of the strands in rear of the ring, a band is clamped around the joined conductor at the point where the individual strands branch off. It will be 45 seen, as shown in Fig. 2, that in the use of the invention the ring is simply placed around some rigid or permanent part, as the handle of the sad iron shown in Fig. 2 and the terminals then placed in connection with 50 their socket pieces, and the result is that any strain upon the attachment cord is taken up by the ring and the terminals are free from all strain. There is no wearing or chafing 55 of the cord, and as the ring presents a perfectly smooth surface to the cords, all possibility of the cord tearing or cutting on the ring is eliminated.

What I claim is:—

In combination with a twin conductor, a 60 ring or eyelet secured at the point where the individual conductors diverge or separate from the twin, a retaining band in rear of the ring, the ring being secured in place by the individual conductors, substantially as 65 described.

In testimony whereof I have affixed my signature in the presence of two witnesses this 29th day of July 1908.

HARRY W. DENHARD.

Witnesses:

FRANK L. OWEN,
A. DIXON.
